A. E. HOWELL,
TYPE WRITING MACHINE,
APPLICATION FILED JUNE 22, 1918.

1,300,216.

Patented Apr. 8, 1919.

UNITED STATES PATENT OFFICE.

ARTHUR E. HOWELL, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,300,216.

Specification of Letters Patent.

Patented Apr. 8, 1919.

Application filed June 22, 1918. Serial No. 241,365.

To all whom it may concern:

Be it known that I, ARTHUR E. HOWELL, a citizen of the United States, residing in Brooklyn borough, in the county of Kings, 5 city and State of New York, have invented certain new and useful Improvements in Type-Writing Machines, of which the following is a specification.

My invention relates to adjustable marginal stop mechanism for typewriting machines, and the object thereof is to provide improved means for disconnecting the locking pawls from the teeth of the rack.

In the Underwood typewriting machine to which my invention is illustrated as applied, it is customary to provide upon each margin gage a forwardly-extending handle, and to provide alongside of said handle a stationary grip, so that when said handle 10 is pressed toward said grip, the stop is released and may be slid to the right or left along the supporting rod, so as to regulate the left or right-hand margin on the typed sheet. An object of my invention is to 15 simplify the construction and operation, and I provide means whereby the handle, if swung either to the right or left, will release the pawl preparatory to sliding the margin gage or block along the supporting 20 rod in the direction in which the handle is being pressed. Thus, it becomes unnecessary to provide any fixed grip or finger rest for coöperation with the handle, and the 25 operation is also simpler. The handle is provided with opposite cams, and a connection 30 in the form of a slide has a part engaging said cams, and the margin gage pawl is operable by said connection. Thus, by a 35 simple and inexpensive structure, which is reliable and readily operated, the margin gage may be instantly released for adjustment in either direction. To conduce to compactness, the handle is mounted upon the under side of the margin block, and 40 the same is true of the pawl; while the connecting device overlies the pawl and also has a part extending down to be engaged by the right and left cams upon the handle.

Each stop comprises a supporting block 45 adjustable along a rod and having a guide extending transversely to said rod, said

rack with which the block engages. Each block has a slidable member movable in and guided by the guide, aforesaid, which slid- 55 able member is operated by a cam pivotally secured to the block, and the inner end of said slidable member is associated with a pawl, which is moved by said cam into and out of engagement with the rack. 60

Other features and advantages will hereinafter appear.

In the accompanying drawing,

Figure 1 is a view showing the front portion of a typewriter frame and carriage 65 with my invention applied thereto, the view being mostly in plan, and portions being broken away to shorten the same.

Fig. 2 is a view showing a section upon a transverse plane indicated by the line 2—2, 70 Fig. 1.

Fig. 3 is a similar view showing a section upon a transverse plane indicated by the line 3—3, Fig. 1.

Fig. 4 is a perspective view, illustrating 75 the elements of the right-hand marginal stop separated, and spaced apart from one another, in order to better illustrate my invention.

Fig. 5 is a similar view showing the ele- 80 ments of the left-hand marginal stop.

Fig. 6 is a view taken upon a transverse plane indicated by the line 6—6, Fig. 1, this view being employed to show the arrangement of the elements of the stop mechanism 85 as a whole, as seen from a position adjacent the right-hand end of the carriage.

The frame 6 has upwardly-extending arms 7 at either end, a side view of one being shown in Fig. 6. These arms serve 90 as supports for two bars or rods extending across the machine, one of which, 8, serves as a support for the right and left-hand marginal stops, while the other, 9, has a series of teeth 10 whereby a rack is provided; this bar also serving as a guide for the right-hand marginal stop.

The rod or bar 8 is supported in bearings in the frame of the machine, and carries a second rack 11, which is loose thereupon, so 100 that the said rack may oscillate in connection with key-locking and bell-ringing mechanisms, not illustrated. This rack is

stop, and the said stop, as it is moved along the bar 8, is guided by the rack 11. Secured to the upper ends of the arms 7 is a bar 12, which extends longitudinally of the machine and carries a scale 13 for use in adjusting the stops, and as a line-scale for the typewriter.

The right-hand marginal stop 14 comprises a block 15 supported by the bar 8 and slideable along the same, said block having a rearwardly-extending portion provided with a guide 16, which engages the rack or bar 9 and guides the stop as it is moved along the rod 8; the said guide serving to hold the stop in proper position relatively to the rod or rack 9 and to hold the locking pawl, to be hereinafter referred to, in proper position relatively to the teeth 10 thereupon, so that it may engage the same.

20 The block 15 carries a swinging cam 17, the same being pivoted at 18 to the under side of the block, said cam having two cam surfaces 19, as best shown in Fig. 4, and a forwardly-extending handle or button 20 whereby it may be swung.

The block 15 is provided with a slot or groove 21, whereby a guide is provided which extends transversely to the rod 8, and 22 designates a slideable member movable in said guide and supported by the block 15, as best shown in Figs. 2 and 4. This sliding member is provided with a downwardly-extending portion 23, the lower end of which terminates in a lug 24, which lug engages 30 with the cam surfaces 19 of the swinging cam 17, whereby longitudinal movement will be imparted to the said slideable member as the cam is moved in either direction from its normal central position. The downwardly-extending arm 23 may be provided with a pin 25 entering a hole provided in the block 15, to thereby assist in guiding the said slideable member as it is operated.

The slideable member 22 is operatively associated with a pawl adapted to engage with and be disengaged from the teeth 10 with which the rack bar 9 is equipped, which pawl may be formed directly upon the inner end of the slideable member, as indicated at 45 26, although said pawl may obviously be formed as an element separate from the slideable member; and 27 designates a spring, the ends of which are connected with a stud 28 carried by the slideable member 22, and 50 25 with a pin 29 carried by the guide block 15 and extending across the inner end of the slideable member 22. The right-hand marginal stop 14 here referred to is equipped with a pointer 30 for use in setting the stop, as is usual in marginal stop mechanism for typewriters and similar machines.

The left-hand marginal stop is designated as a whole by the reference numeral 31 in Fig. 1. This marginal stop, as above explained, is slideable along the rod 8, the same

as the right-hand marginal stop 14; and the same comprises a block 32 slideable along said rod, and the rear portion of which is provided with a depending lug 33, which has a hook-shaped end extending beneath the rear edge of the rack 11, so that the stop will be properly guided by the rack; and so that movement communicated to the said block will be transmitted to the rack 11 carried thereby, as above explained, to thereby oscillate the same and operate the bell-ringing and key-locking mechanisms of the machine when such mechanisms are used in conjunction with the marginal stop mechanism to which this invention relates. The movement referred to is communicated to the block 32 by means of a bar 34 carried by and located at the rear end of the block, and which bar is shown as provided with cams 35 for operating the bell-ringing and key-locking mechanisms, and with which cams a lug 36, carried by the carriage 37 of the typewriter, engages, to thereby depress the bar 34 and communicate a slight angular movement to the rack 11, as explained. The bar 34 is provided with a lug 38 at its left-hand extremity with which the lug 36 on the carriage engages, to thereby arrest the movement of the carriage to the left, as will be appreciated.

95 The block 32 of the left-hand marginal stop is likewise provided with a guide 39 within which a transversely movable sliding member 40 operates, and 41 designates a swinging cam member having two cam surfaces 42. This cam member is pivotally supported upon the under side of the block 32 by means of a screw 43, or otherwise; the construction of the cam 41 being preferably identical with that of the cam 17, hereinbefore referred to.

100 The transversely slideable member 40 is provided with a depending arm 44 having a lug 45 at its lower end, which lug engages with the cam surfaces 42 of the cam member 41, whereby reciprocating motion, in a direction transverse to the supporting rod 8, is imparted to the sliding member 40 as the cam is swung upon its pivotal support 43 either to the right or left from its neutral 105 central position.

110 The sliding member 40 is operatively associated with a pawl which engages the rack 11, to thereby lock the left-hand marginal stop in whatever position it may be adjusted, the same as in the case of the right-hand marginal stop, to which end the said sliding member is shown as provided with a depending pin 46 located adjacent its inner end, and which pin extends downward and 115 through a hole 47 provided in the block 32, and into a hole provided in a swinging pivotally supported pawl 48; said pawl being secured to and carried by the supporting block 32 by means of a screw 49 extending 120

through a hole 50 provided in the said pawl, or otherwise; the pawl being forced in a rearward direction by a spring 51, the arrangement and operation of which will be obvious from Fig. 5 of the drawings.

It therefore follows that as the cam 41 is oscillated upon its pivotal support 43 reciprocating motion will be communicated to the slidable member 40, and the pawl 48 will be operated through the depending pin 46, which is in operative engagement therewith, as above explained. The left-hand marginal stop likewise is provided with a pointer 52 for use in setting the same, the same as in the case of the right-hand stop.

Variations may be resorted to within the scope of the invention, and portions of the improvements may be used without others.

Having thus described my invention, I claim:

1. Adjustable marginal stop mechanism for typewriters and similar machines comprising a supporting rod; a block or support supported by and slidable along said rod; a swinging cam carried by and pivotally connected with said block; a slidable member carried by said block and movable relatively thereto in a direction transverse to said supporting rod, and which member is operated by said cam; and a pawl with which said slidable member is operatively associated, and which pawl is adapted to engage a rack to thereby lock said block in place.

2. Adjustable marginal stop mechanism for typewriters and similar machines comprising a supporting rod; a block or support supported by and slidable along said rod; a rack with which said block engages and by which the same is guided as it moves along said rod; a swinging cam carried by and pivotally connected with said block; a slidable member carried by said block and movable relatively thereto in a direction transverse to said supporting rod, and which member is operated by said cam; and a pawl with which said slidable member is operatively associated, and which pawl is adapted to engage said rack to thereby lock said block in place.

3. Adjustable marginal stop mechanism for typewriters and similar machines comprising a supporting rod; a block or support supported by and slidable along said rod, and which block is provided with a guide extending transversely to said rod; a rack with which said block engages and by which the same is guided as it moves along said rod; a swinging cam carried by and pivotally connected with said block; a slidable member operated by said cam and movable transversely to said supporting rod, and which member is guided in its movement by said guide; and a pawl with which said slidable member is operatively con-

nected, and which pawl is adapted to engage said rack to thereby lock said block in place.

4. Adjustable marginal stop mechanism for typewriters and similar machines comprising a supporting rod; a block or support supported by and slidable along said rod, and which block is provided with a groove in its upper side and extending transversely to said rod; a rack with which said block engages and by which the same is guided as it moves along said rod; a swinging cam pivotally connected with said block and located upon the under side thereof; a slidable member movable in said groove and having a depending portion provided with a lug adapted to engage said cam; and a pawl with which said slidable member is operatively connected, and which pawl is adapted to engage said rack to thereby lock said block in place.

5. Adjustable marginal stop mechanism for typewriters and similar machines comprising a supporting rod; a block supported by and slidable along said rod; a rack with which said block engages and by which the same is guided as it moves along said rod; a swinging cam carried by and pivotally connected with said block; a slidable member carried by said block and movable relatively thereto in a direction transverse to said supporting rod, and which member is operated by said cam; and a pawl carried by said slid- 95 able member and located at the free end thereof, and which pawl is adapted to engage said rack to thereby lock said block in place.

6. Adjustable marginal stop mechanism for typewriters and similar machines comprising a supporting rod; a block or support supported by and slidable along said rod; a rack with which said block engages and by which the same is guided as it moves along said rod; a swinging cam carried by and pivotally connected with said block; a slid- 105 able member carried by said block and movable relatively thereto in a direction transverse to said supporting rod, and which member is operated by said cam; a pawl pivotally connected with said block and adapted to engage said rack to thereby lock said block in place; and means whereby motion imparted to said slidable member by said cam is transmitted to said pawl, to thereby move the same out of engagement with said rack.

7. Adjustable marginal stop mechanism for typewriters and similar machines comprising a supporting rod; a block or support supported by and slidable along said rod, and which block is provided with a groove in its upper side extending transversely to said rod; a rack with which said block engages and by which the same is guided as it moves along said rod; a swing- 125 130

- 1 ing cam pivotally connected with said block and located upon the under side thereof; a slideable member movable in said groove and having a depending portion provided with a lug adapted to engage said cam; a pawl carried by and pivotally connected with said block; and a pin carried by said slideable member and extending into a hole provided in said pawl.
- 10 8. In a marginal stop mechanism for typewriters, the combination with a supporting rod and a margin-controlling block adjustable therealong, of a pawl on said block, a rack to engage with said pawl, a handle pivoted on said block to swing to either right or left, opposite cams upon said handle, and a device operable by said cams and extending to said pawl to release the same when the handle is swung in either direction.
- 15 9. In a marginal stop mechanism for typewriters, the combination with a supporting rod and a margin-controlling block adjustable therealong, of a pawl on said block, a rack to engage with said pawl, a handle pivoted on said block to swing to either right or left, opposite cams upon said

handle, and a device operable by said cams and extending to said pawl to release the same when the handle is swung in either 30 direction, said releasing device in the form of a slide which is guided upon said block.

10. In a marginal stop mechanism for typewriters, the combination with a supporting rod and a margin-controlling block 35 adjustable therealong, of a pawl on said block, a rack to engage with said pawl, a handle pivoted on said block to swing to either right or left, opposite cams upon said handle, and a device operable by said cams 40 and extending to said pawl to release the same when the handle is swung in either direction, said releasing device in the form of a slide which is guided upon said block, said handle and said pawl pivoted upon the 45 under side of said block, and said slide overlying said pawl and having a part extending down to said handle for engagement by the cams thereon.

ARTHUR E. HOWELL.
